MACHINE FOR APPLYING EARS TO PAILS.

1,423,693.

Specification of Letters Patent. Patented July 25, 1922.

Application filed August 9, 1920. Serial No. 402,406.

To all whom it may concern:

Be it known that I, WILLIAM SPAIN, a citizen of the United States, residing at Riverside, in the county of Cook and State of Illinois, have invented certain new and useful Improvements in Machines for Applying Ears to Pails, of which the following is a specification.

My invention relates to pail forming machines, and more particularly to a machine for positioning the handle-receiving ears of a pail on opposite sides of the pail body, and securing the ears in such position preliminary to the soldering or other means employed for effecting permanent attachment of the ears to the pail body.

This invention is in the nature of an improvement upon the apparatus disclosed in my United States Letters Patent No. 929,798, granted August 3, 1909, and has for one of its objects to provide novel and improved means whereby the handle-receiving ears of a pail may be accurately positioned on opposite sides of the pail body and the pail discharged from the machine without danger of distorting or otherwise damaging the ears or pail, and without danger of subsequently displacing the ears from their proper positions when the pail is discharged from the machine.

Another object is to provide in a machine of the above general character, improved ear supporting and positioning mechanism which will support and position pail ears of various contours, which may be conveniently and accurately adjusted when such adjustment is necessary, and which when applying imperfectly formed ears to pails, or when applying perfectly formed ears to imperfectly formed pails, will automatically adjust itself so as to avoid damaging said pails or ears.

The invention has for further objects the novel arrangements, constructions, and combinations of parts hereinafter described and claimed for carrying out the above stated objects and such other objects as may appear from the following description.

A preferred embodiment of my invention is illustrated in the accompanying drawings wherein—

Figure 1 is a side view in elevation of a machine constructed in accordance with my invention, certain parts of the apparatus be-

ing broken away for the purpose of clear- 55
ness;

Fig. 2 is a plan view of the structure shown in Fig. 1;

Fig. 3 is a vertical cross-section taken through the machine on line 3—3 of Fig. 2; 60

Fig. 4 is a detail view of a friction-producing element shown in the preceding figures, for holding certain intermittently operable members of the machine in a stationary position at certain times during the operation of the machine; 65

Fig. 5 is a view in elevation of a plunger and head employed in the machine to shift the position of the pail during the positioning of the pail ears; 70

Fig. 6 is a fragmentary view in elevation of one of the pail-supporting disks, illustrating a preferred mechanism for supporting the pail ears;

Fig. 7 is a sectional plan view taken on 75
line 7—7 of Fig. 6;

Fig. 8 is a vertical section taken on line 8—8 of Fig. 6 and illustrating the position of the plunger head (shown in Fig. 5) and the pail body immediately prior to moving 80
the ears into engagement with the pail body; and

Fig. 9 is a fragmentary view in perspective of the upper portion of the pail, showing a handle-receiving ear in its applied position, the upper edge of said ear being inserted between the body of the pail and the depending flange of the pail cover. 85

Like characters of reference designate corresponding parts throughout the several 90
figures of the drawings.

The preferred embodiment of my invention consists of two oppositely disposed drums, designated generally by reference numerals 10, 11, which drums are made up 95
in each case of two disks 12, 12^a, and 13,
13^a, secured to parallel shafts 14, 15, and formed on their peripheries with recesses providing pockets 16, 17 for the pail bodies. The drums are rotated in unison in opposite 100
directions, so that a pail body discharged from the chute 18 will enter a pocket 16 of the drum 10 and will be conveyed toward a complementary pocket 17 of the drum 11. The drums are so spaced with relation to 105
each other that when they are rotated the corresponding pockets of the drums successively cooperate with each other to provide

substantially cylindrical supports for the pail bodies as they reach predetermined points in their movement through the machine. The drums are preferably operated 5 intermittently so that as each cylindrical support for the pail body is formed the rotation of the drums is interrupted for a time sufficient to permit other intermittently operated mechanism, hereinafter described, to 10 move the ears 19, 19, previously inserted in ear-retaining chucks 20, 20^a by the attendant, to be brought into engagement with the cylindrical wall of the pail body at diametrically opposite points, and the pail body 15 moved longitudinally to force the ends of the ears between the wall 21 and cover flange 22 of the pail, as shown in Fig. 9 of the drawings.

The drums are operatively connected with 20 each other by means of intermeshing gears 23, 24, secured to the drum shafts 14, 15, and may be given the desired intermittent movement by any suitable means. In the drawings I have shown a slot wheel 25 and pin 25 gear 26 for accomplishing this result. The slot wheel 25 consists of a disk secured to the outer face of the spur gear 24 and provided with a plurality of relatively deep radially extending slots 27, the number of slots corresponding to the number of pockets of each 30 of the drums 10, 11. The pin gear 26 is preferably a spur-toothed gear formed on its inner face with two diametrically disposed studs 28, 28 adapted when the gear is rotated to alternately enter the slots 27 of the wheel 25 so as to rotate the drums a distance necessary to form a cylindrical pocket for the pail for each one-half rotation of the pin gear. The pin gear is secured to a shaft 29, 40 and is in mesh with the continuously operated pinion 30 on the drive shaft 31.

In order to prevent the handle-receiving ears of the pail from being distorted or displaced from their applied position on the 45 pail when the pail is being discharged from the machine, and also to obtain other advantages disclosed herein, I preferably arrange and operate the ear-retaining chuck 20, 20^a so that the ears 19 inserted in the chucks by 50 the attendant will be normally held out of engagement with the pail body until the rotational movement of the drums 10, 11 is interrupted, whereupon the ear-positioning mechanism is brought into operation to position the ears on the pail body and to then 55 permit the ear-retaining chucks to move to their retracted position before the drums are rotated to discharge the pail with the ears applied.

60 The ear-retaining chucks 20, 20^a are slidably supported in radial slots 32 formed on the forward face of the disks 12, 13, and consist in each case of a channel-shaped body 33, end plate 34, horseshoe magnet 35 adapted 65 to hold the ears in the chucks while the

drums rotate from one position to another, and side closure plate 36 screwed to the body of the chuck so as to provide a clamping device to hold the said magnet in position. The body is preferably made of non-magnetic metal and is retained in the slot 32 by 70 guide strips 37. A gasket of non-magnetic material is preferably inserted between the magnet and closure plate. The end plate 34 is formed with an opening 38 adapted to receive the boss 39 of the pail ear when the same is inserted in the chuck, and is preferably detachably secured to the body 33 by screws 40, so as to permit another end plate 75 to be substituted for the one shown, when it is desired to apply ears of different contour. The ear-retaining chucks are normally held in their retracted position by means of springs 41 positioned in pockets 42 on the rear face of the chuck body 33, which springs 80 bear against studs 43 projecting from the outer face of the disks and extending into the spring pockets. These studs, together with studs 44, provide stops to limit the inward movement of the chucks 20, 20^a. The 85 ears are inserted in the chucks by the attendant before the pail bodies enter the pockets, the magnets having been first adjusted to suit the depth of the boss 39 of the ears being applied to the pails. The pail bodies together with their previously applied covers or rims 45 are discharged into the pockets so that the cover flange 22 of the pail will be 90 positioned beyond the edge of the ears as shown in Figs. 2 and 8. The pail bodies in this position are conveyed to the point where the rotation of the drums 10, 11 is interrupted and the ears are brought into engagement with the pail wall at a point back of the said 95 cover flange. The pail bodies are then moved longitudinally by means of a plunger head 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

nutely adjusted by means of the adjusting screws 56 and firmly held in such position so that when the ear chucks of the complementary pockets of the drums 10, 11 have been moved 5 outwardly sufficient to bring the ears into contact with the wall of the pail body, the lugs 54, 54^a of the plunger head will ride off the cam surface 57 (Fig. 8) of the lugs 55, 55^a before the plunger head 46 engages with 10 the cover end of the pail. Further inward movement, however, of the plunger head brings it into engagement with the cover end of the pail and the pail body is forced longitudinally in the direction indicated by the 15 arrows in Figs. 2 and 8, during which movement of the pail body the ends of the ears find entry between the wall and cover flange of the pail. The plunger head and chucks are then moved in the opposite direction and 20 the drums 10, 11 rotated to discharge the pail body to which the ears have been applied.

In order to prevent the inertia of the intermittently operated elements from moving them beyond the point where it is desired that they remain in a stationary position, I preferably provide a split friction band 59 attached to the frame 60 of the machine, so as to grip a drum 61 secured 25 to the drum shaft 15. The frictional grip of the band 59 may be varied to suit conditions by adjusting the hand-nut 62 (Fig. 4).

When applying ears of this character, the ends of the ears are preferably forced between the wall of the pail and cover flange 30 the entire width of the flange until their ends engage the inner surface of the cover. If under such conditions one of the ears be slightly longer than the other, or if for 35 any reason there be a greater pressure exerted against one ear than the other, there is danger of damaging the ear. In order to avoid an unequal pressure being exerted against the opposite edges of the pail body 40 or on the ears being applied thereto, I preferably mount the plunger head 46 on the squared shaft 50 so that it will pivot on a vertical axis. The pivoted connection consists of a pin 63 extending vertically through 45 the shaft 50 and fitting in small recesses 64 (Fig. 5) in the plunger head. The plunger is held in contact with the pivot pin 63 by 50 means of a resilient member 65, preferably a rubber block, interposed between the plunger head and a shoulder 66 on the shaft 50, 55 so that the plunger head will be normally held in a plane at right angles to the length of the shaft 50. With this arrangement, the plunger head has capacity to assume an angular position with relation to the shaft 50 60 to compensate for any irregularity of the edge of the pail body or any objectionable variation in the length of the ears being applied to the pail. The rubber block 65 is preferably stiff enough to avoid any varia-

tion in the tension of the springs 41 displacing it from its normal position.

While I have described my invention in one specific embodiment, it will be obvious that various modifications in structure 70 might be made without departure from the spirit of my invention. I therefore contemplate all such modifications coming within the scope of the appended claims.

75

I claim:

1. In apparatus for applying handle-receiving ears to pails, the combination with a support for a pail body adapted to support said body in a position to receive an ear, of an ear-retaining device adapted to normally hold an ear out of contact with said pail body, and mechanism for producing relative movement as between said support and ear-retaining device to position said ear against the pail body.

85

2. In apparatus for applying handle-receiving ears to pails, the combination with a support for a pail body, of an ear-retaining device adapted to normally hold an ear out of contact with said pail body, and mechanism for operating said device to move the same toward the pail body to position said ear thereon, said operating mechanism being adapted to release said device so as to permit its return to its normal position after the ear is applied.

90

3. In apparatus for applying handle-receiving ears to pails, the combination with an intermittently operated conveyer for a pail body, of an ear-retaining device adapted 100 to normally hold an ear out of contact with said pail body, and mechanism for operating said device during the period that the said conveyer is at rest, to move said device toward the pail body to position said ear 105 thereon; said operating mechanism being adapted to release said device so as to permit its return to its normal position after the ear is applied.

105

4. In apparatus for applying handle-receiving ears to pails, the combination with a conveyor adapted to support a pail body together with its previously applied cover rim in a predetermined position, of ear-positioning devices adapted to move ears into 110 contact with opposite sides of the pail body while the pail body is in said predetermined position and maintain said contact until the ears are attached to said body, and means for producing relative movement as between 115 said pail body and ears while the ears are held in contact with said body whereby the ends of said ears are forced between the wall and cover rim of the pail.

120

5. In apparatus for applying handle-receiving ears to pails, the combination with an intermittently operated conveyor adapted when at rest to support a pail body 125 in a predetermined position, of intermittently operated ear-retaining chucks adapted 130

- to move ears into contact with opposite sides of the pail body while said conveyor is at rest, and mechanism for effecting an attachment of said ears to the pail body.
- 5 6. In apparatus for applying handle-receiving ears to pails, the combination with an intermittently operated conveyor adapted when at rest to support a pail body and its applied cover in a predetermined position, 10 of intermittently operated ear-retaining chucks adapted to move ears into contact with opposite sides of the pail body while said conveyor is at rest, and mechanism for forcing said ears between the wall and cover flange of the pail to effect an attachment of said ears to the pail body.
7. In apparatus for applying handle-receiving ears to pails, the combination with an intermittently operated conveyor adapted 20 when at rest to support a pail body and its applied cover in a predetermined position, of intermittently operated ear-retaining chucks adapted to move ears into contact with opposite sides of the pail body 25 while said conveyor is at rest, and mechanism for shifting the pail body longitudinally to force said ears between the wall and cover flange of the pail to effect an attachment of said ears to the pail body.
- 30 8. In apparatus for applying handle-receiving ears to pails, the combination with an intermittently operated conveyor adapted when at rest to support a pail body and its applied cover in a predetermined position, 35 of intermittently operated ear-retaining chucks a pair of which operate in unison to move ears into contact with opposite sides of the pail body while said conveyor is at rest, and mechanism for shifting the pail 40 body longitudinally to force said ears between the wall and cover flange of the pail to effect an attachment of said ears to the pail body.
9. In apparatus for applying handle-receiving ears to pails, the combination with a conveyor for a pail body and its previously applied cover rim, of magnets carried by said conveyor adapted to retain said ears, and intermittently operated mechanism 45 for moving said magnets with relation to said conveyor to bring said ears against the wall of the pail and for forcing the ends of said ears between the wall and cover rim of the pail.
- 50 10. In apparatus for applying handle-receiving ears to pails, the combination with a conveyor for a pail body and its previously applied cover rim, of magnets carried by said conveyor adapted to retain said ears, and intermittently operated mechanism 55 for imparting movement to said magnets to bring said ears against the wall of the pail and for moving the pail longitudinally to force the ends of said ears between the wall 60 and cover rim of the pail.
- 65 11. In apparatus for applying handle-receiving ears to pails, the combination with means for supporting a pail body and its previously applied cover rim, of ear-retaining chucks comprising, in each case, a body 70 providing a seat for an ear and a magnet adjustably supported on said body adapted to hold said ear on the said seat, and mechanism for operating said chucks with relation to said pail supporting means to bring 75 the ears retained into contact with opposite sides of said pail.
12. In apparatus for applying handle-receiving ears to pails, the combination with means for supporting a pail body and its previously applied cover rim, of ear-retaining chucks comprising, in each case, a body 80 providing a seat for an ear and a magnet adjustably supported on said body adapted to hold said ear on the said seat, and mechanism for operating said chucks to bring the ears retained into contact with opposite sides of said pail comprising a plunger adapted 85 to force the ends of the ears between the wall and cover rim of the pail.
- 90 13. In apparatus for applying handle-receiving ears to pails, the combination with means for supporting a pail body and its previously applied cover rim, of ear-retaining chucks comprising, in each case, a body 95 providing a seat for an ear and a magnet adjustably supported on said body adapted to hold said ear on the said seat, and mechanism for operating said chucks to bring the ears retained into contact with opposite sides of said pail, comprising a plunger 100 adapted to move the pail body longitudinally to force the ends of the ears between the wall and cover rim of the pail.
14. In apparatus for applying handle-receiving ears to pails, the combination with means for supporting a pail body and its previously applied cover rim, of ear-retaining chucks, and mechanism for moving said chucks to bring the ears into contact with 110 the wall of the pail comprising a plunger provided with cam lugs adapted to engage with two oppositely disposed chucks.
15. In apparatus for applying handle-receiving ears to pails, the combination with 115 means for supporting a pail body and its previously applied cover rim, of ear-retaining chucks, and mechanism for moving said chucks to bring the ears into contact with the wall of the pail comprising a plunger 120 provided with cam lugs adapted to engage with two oppositely disposed chucks, said cam lugs being adjustable to vary the movement of said chucks.
16. In apparatus for applying handle-receiving ears to pails, the combination with 125 means for supporting a pail body and its previously applied cover rim, of ear-retaining chucks, and mechanism for moving said chucks to bring the ears into contact with 130

- the wall of the pail comprising a plunger provided with cam lugs adapted to engage with two oppositely disposed chucks, said plunger being adapted to engage with the 5 pail body to move the same longitudinally whereby the ends of said ears are forced between the wall and cover rim of the pail, and said cam lugs being adjustable to vary the movement of said chucks.
- 10 17. In apparatus for applying handle-receiving ears to pails, the combination with means for supporting a pail body and its previously applied cover rim, of ear-retaining chucks, and mechanism for moving said 15 chucks to bring the ears into contact with the wall of the pail comprising a plunger shaft, a plunger head yieldably supported on said shaft, and provided with cam lugs adapted to engage with two oppositely disposed 20 chucks, said plunger being adapted to engage with the pail body to move the same longitudinally whereby the ends of said ears are forced between the wall and cover rim of the pail, and said cam lugs being adjustable to vary the movement of said 25 chucks.
18. In apparatus of the character described, the combination with oppositely disposed drums formed with complementary recesses which cooperate one with another to provide a composite pocket adapted to support a pail body and its previously applied cover rim, and means for intermittently operating said drums whereby a pail body is 30 maintained in said composite pocket while the drums are at rest, of ear-retaining chucks carried by said drums and disposed on opposite sides of the pail when said composite pocket is formed, means for moving 35 the ears retained by said chucks into contact with the wall of the pail while said drums are at rest, and means for producing relative movement as between the ears and pail to force the end of the ears between the wall and cover rim of the pail.
- 40 19. In apparatus of the character described, the combination with oppositely disposed drums formed with complementary recesses which cooperate one with another to provide a composite pocket adapted to support a pail body and its previously applied cover rim, and means for intermittently operating said drums whereby a pail body is 45 maintained in said composite pocket while the drums are at rest, of ear-retaining chucks carried by said drums and disposed on opposite sides of the pail when said composite pocket is formed, means for moving the ears retained by said chucks into contact with the wall of the pail while said drums are at rest, and means for imparting longitudinal movement to the pail to force the ends of the ears between the wall and cover rim of the pail.
- 50 20. In apparatus of the character described, the combination with oppositely disposed drums formed with complementary recesses which cooperate one with another to provide a composite pocket adapted to support a pail body and its previously applied cover rim, and means for intermittently operating said drums whereby a pail body is 55 maintained in said composite pocket while the drums are at rest, of ear-retaining chucks carried by said drums and disposed on opposite sides of the pail when said composite pocket is formed, means for moving the ears retained by said chucks into contact with the wall of the pail while said drums are at rest, and means for imparting longitudinal movement to the pail to force the ends of the ears between the wall and cover rim of the pail.
- 60 21. In apparatus of the character described, the combination with oppositely disposed drums formed with complementary recesses which cooperate one with another to form a composite pocket, means for intermittently operating the drums whereby a pail positioned in one of said recesses is conveyed to the point where the said composite pocket is formed, of ear-retaining chucks slidably supported on said drums adjacent said recesses and adapted to normally support ears out of contact with the pail body, means operative while the said drums are at rest to move said chucks outwardly to bring the ears retained thereby into contact with the pail body and for attaching the ears to the pail, and means effective to return said chucks to their normal position during said rest period of the drums.
- 65 22. In apparatus of the character described, the combination with oppositely disposed drums formed with complementary recesses which cooperate one with another to form a composite pocket, means for intermittently operating the drums whereby a pail positioned in one of said recesses is conveyed to the point where the said composite pocket is formed, of ear-retaining chucks slidably supported on said drums adjacent said recesses and adapted to normally support ears out of contact with the pail body, means operative while the said drums are at rest to move said chucks outwardly to bring the ears retained thereby into contact with the pail body and for attaching the ears to the pail comprising a plunger head provided with cams adapted to engage with chucks to impart an outward movement thereto; said plunger head being adapted to subsequently engage the pail body to move it longitudinally whereby the ends of the ears are forced between the wall and the cover flange of the pail.
